UNITED STATES PATENT OFFICE.

WILLIAM W. WILSON, OF LOS ANGELES, CALIFORNIA.

PUMP.

1,321,174.

Specification of Letters Patent. Patented Nov. 11, 1919.

Application filed April 23, 1915. Serial No. 23,503.

To all whom it may concern:

Be it known that I, WILLIAM W. WILSON, a citizen of the United States, residing at Los Angeles, in the county of Los Angeles 5 and State of California, have invented new and useful Improvements in Pumps, of which the following is a specification.

This invention relates to pumps, and more particularly to pump operating means, and 10 it has for its object to provide improvements in mechanism of this character which will be generally superior in point of relative simplicity and inexpensiveness of construction combined with positiveness and efficiency of operation, compactness in form, 15 economy in power and freedom from frictional losses and wear and tear and which will be generally superior in efficiency and serviceability. With the above and other 20 objects in view, the invention consists in the provision, construction, formation, combination, association and interrelation of parts, members and features all as hereinafter described, shown in the drawings and finally 25 pointed out in claims.

In the drawings:

Figure 1 is a side elevation of an improved pump mechanism embodying the invention, parts of the well-mouth structure 30 being in vertical section upon the line x^1-x^1 , Fig. 2.

Fig. 2 is a front elevation of the same mechanism, similar parts being similarly sectioned vertically upon the line x^2-x^2 , 35 Fig. 1; and,

Fig. 3 is a transverse sectional view taken on the line x^3-x^3 , Fig. 1, and looking downwardly.

Corresponding parts in all the figures are 40 designated by the same reference characters.

Referring with particularity to the drawings, the improved pump mechanism is shown therein as provided for operating a pump rod A and a pump rod sleeve B 45 which, in usual practice are oppositely reciprocated, the former within the latter, and are respectively connected with the valved pistons (not shown) in the pump barrel. The particular organization or type, location and accommodation of the valved pump 50 pistons is immaterial so far as the factors of the present invention are concerned, and it is understood that they with the pump barrel will be disposed at the proper point in the 55 well so as to co-act in elevating the water or other fluid through the pump. The pump

rod sleeve B is shown as playing through a casing head C at the mouth of the well, the same being provided with a suitable watertight gland or stuffing box. To provide for 60 direct actuation of the pump rod sleeve B I provide a pair of spaced actuating rods 4 and 5 which are connected with the upper end of the pump rod sleeve B by a cross head 6 through which the pump rod A reciprocates, such cross head being coupled onto the upper end of the pump rod sleeve B and provided with a suitable gland or stuffing box 7. The pump rod A is thus disposed intermediate of the two drive or connecting 65 rods 4 and 5 which are ranged in a group each spaced from the others. Surrounding and rising above the mouth of the well is a suitable masonry or concrete base 8, upon which is disposed the driving means D for 70 the pump rod A and pump rod sleeve B; such driving means including three separate members or groups of working parts, d, e and f which respectively actuate the drive rods 5 and 4, and the pump rod A. 75 The drive means D comprises three cranks, 9, 10 and 11, one for each of the drive means members d, e and f respectively, and three connecting rods, 12, 13 and 14 operatively coupling said cranks respectively with the 80 drive rods 5 and 4 and the pump rod A respectively; said cranks being comprised within a unitary crank device g journaled at its ends, as at 15 and 16, in upright frame members 17 and 18 disposed upon the base 8; said frame members 17 and 18 having horizontal base portions 17^a and 18^a resting directly upon the base 8 and ranging rearwardly from the forward portion thereof. Rising from said base frame members 17^a and 18^a are vertical frame members 17^b and 18^b carrying journals for a drive shaft 19 carrying at one end a drive wheel 20 adapted to be driven by a belt or otherwise through a suitable prime mover and carrying at the other end a pinion 21 meshing with a gear 22 fixed to the end of the unitary crank device g. The base frame members 17^a and 18^a are likewise provided at their rearward extremities with upwardly 95 and forwardly angled frame members 17^c and 18^c between which ranges a fixed shaft 23 from which depend three links 24^a, 24^b and 24^c; and separate alinement arms 25^a, 25^b and 25^c are pivotally connected each at 100 105 its rearward end with a separate one of said links last mentioned, as at 26^a, 26^b and 110 26^c.

26° respectively; said alinement arms being arranged in a transverse series, and respectively pivotally connected at their forward ends, as at 27^a, 27^b and 27^c, with the drive 5 rod 5, the pump rod A and the drive rod 4, at the point of pivotal connection of said drive rods and pump rod with the connecting rods 12, 14 and 13.

Alinement arm guide means E are provided for properly phasing the play of the alinement arms 25^a, 25^b and 25^c, in the movement of said alinement arms responsive to play of the drive rods 4 and 5 and the pump rod A under crank and connecting rod actuation, which movement of which alinement arms is permitted or accommodated by the links 24^a, 24^b and 24^c; such alinement arm guide means so determining the consequent movement of the alinement 15 arms that the points of connection of the respective alinement arms with the respective connecting rods and the respective drive rods and pump rod shall traverse rectilinear paths of movement, and the 20 drive rods and pump rod be thus caused to traverse similar rectilinear or straight away paths of movement, avoiding wear and tear and frictional losses which would otherwise be present incident to untrue 25 movement or distortion of the paths of movement from the rectilinear. These alinement arm guide means are disclosed in the drawings as comprising a fixed transverse shaft 28 ranging between the frame 30 base members 17^a and 18^a, and links 29^a, 29^b and 29^c respectively, pivotally connected each at one end with said shaft 28 and at the other end with a separate one of the alinement arms. In order to accommodate 35 the alinement arms in their operative play, each of the same is preferably formed into a central open frame portion 25^d within which frame portions of each series of alinement arms, the shaft 28 is disposed. In 40 order to provide for proper balance as among the working parts directly related to the pump rod A and the pump rod sleeve B, due to duplication of connections between the crank element G and the pump 45 rod sleeve B, the pump rod A and its connecting rod 14, and its alinement arm 25^b, the link 29^b, and the incidental features and adjuncts of this mechanical grouping, are made of such total mass as to correspond 50 in the aggregate to the total mass of material entering into the corresponding parts and features of the members d and e of the drive means D, the drive rods 5 and 4 and the attendant corresponding features. 55

The operation, method of use and advantages of the improvements in pumps or pump mechanism constituting the invention, will be readily understood from the foregoing description, taken in connection 60 with the drawings and the following state- 65

ment, all with respect to the embodiment of the invention herein disclosed.

Power is applied from the drive shaft 19 to the crank element or device g causing the connecting rods d, e and f to actuate the drive rods 5 and 4 and the pump rod A, the drive rods in turn in their reciprocation reciprocating the pump rod sleeve B; and the set of the various cranks 9, 10 and 11 is such that the cranks 9 and 10 are 180° spaced from the crank 11, whereby the pump rod A will complete the downward phase of its excursion as the pump rod sleeve B completes the upward phase of its excursion. All of this of course may be varied with the requirements of any particular service, so as to produce the desired or required piston strokes. The throw of the connecting rods 12, 13 and 14 consequent upon crank actuation tends to cause the drive 75 rods 5 and 4 and the pump rod A to execute movements of oscillation as well as reciprocatory, or, in other words, to execute movements which depart somewhat from a straight away rectilinear nature. In order 80 to prevent such departure, and to cause the pump rod and drive rods, together with the pump rod sleeve connecting with the drive rods, to execute true rectilinear movements, and thus avoid the otherwise present frictional loss, binding and wear and tear, the alinement arms 25^a, 25^b and 25^c are provided, the same acting to cause true rectilinear movement of the driven parts. These 85 alinement arms are phased by the alinement 90 arm guide means E, as set forth, so that the pump rod and the pump rod sleeve are held to true rectilinear movement, the links 29^a, 29^b and 29^c definitely determining the 95 play of the alinement arms as permitted by 100 their suspension from the three links 24^a, 24^b and 24^c. In other words, during either 105 lift or fall of either one of the drive rods 5 and 4 or of the pump rod A, the respective 110 alinement arm is permitted to execute only 115 such compensatory movement as will permit true straight away or rectilinear movement of the pump rod and the drive rods and their connecting pump rod sleeve. Through 120 the agency of such alinement arms and alinement arm guide means having the function set forth, all of the disadvantageous operative aberrations customarily attending crank driven pump rod movement are eliminated.

The casing head C is provided with the usual lateral discharge pipe F for the outflow of the pump.

It is manifest that many changes and modifications may be made in variation 125 from the specific construction and interrelation of parts, members and features disclosed in the drawings and herein described, without departing from the spirit of the invention and a fair interpretation thereof. 130

Having thus disclosed my invention, I claim and desire to secure by Letters Patent:

1. In a pump, a pump rod or sleeve, means for reciprocating the same, and means for holding the pump rod to rectilinear movement in the reciprocation thereof; said latter means comprising an alinement arm, means constraining one end thereof to execute a definite path of movement, the other end thereof being pivotally connected with the pump rod, and guide means determining the path of movement of said alinement arm; and consisting of a link pivotally connected at one end with a stationary support and pivotally connected at the other end with said alinement arm; said alinement arm having an enlarged opening intermediate of its ends, and a shaft being provided ranging through said opening and constituting the stationary support for one end of said link.

2. A pump, comprising a pump rod, a pump rod sleeve within which the pump

rod reciprocates, drive rods connected with 25 the pump rod sleeve, means for oppositely reciprocating the pump rod sleeve drive rods and the pump rod, three alinement arms each of which is provided at one end with means constraining said end thereof 30 to execute a definite path of movement and each of which at the other end is pivotally connected with one of the said drive rods or said pump rod, each of said alinement arms being provided with an enlarged opening intermediate of its ends, a shaft ranging through said alinement arm openings, and three links respectively connected with said alinement arms each at one end and with said shaft each at the other end.

In testimony whereof I have signed my name to this specification in the presence of two subscribing witnesses.

WILLIAM W. WILSON.
